CORNEAL RUST RING REMOVER

David E. Staub, Clearwater, Fla., assignor to
Concept, Inc., St. Petersburg, Fla.

Filed Mar. 31, 1971, Ser. No. 130,048

Term of patent 14 years

Int. Cl. D24—02

U.S. Cl. D83—12

FIG. 1

FIG. 2

FIG. 3

FIG. 4

FIG. 1 is a side elevation of the corneal rust ring remover.

FIG. 2 is a view similar to that of FIG. 1 in which the said rust ring remover is rotated through an arc of 45° from that shown in FIG. 1.

FIG. 3 is a front end view of the device as it appears from left to right in FIG. 2.

FIG. 4 is a rear end view of the rust ring remover as viewed in either of FIG. 1 or 2.

I claim:
The ornamental design for a corneal rust ring remover, as shown.
